UNITED STATES PATENT OFFICE.

FREDERICK RUFENACHT, OF BUCYRUS, OHIO.

DESIGN FOR A TIRE TREAD.

60,705.

Specification for Design. Patented Mar. 21, 1922.

Application filed April 29, 1921. Serial No. 465,538. Term of patent 3½ years.

To all whom it may concern:

Be it known that I, FREDERICK RUFENACHT, a citizen of the United States, residing at Bucyrus, in the county of Crawford and State of Ohio, have invented a new, original, and ornamental Design for a Tire Tread, of which the following is a specification, reference being had to the accompanying drawing, forming part thereof.

In the accompanying drawing:

Figure 1 is a plan view of a tire, showing my new design;

Figure 2 is a transverse sectional view on line 2—2 of Figure 1; and

Figure 3 is a transverse sectional view on line 3—3 of Figure 1.

I claim:

The ornamental design for a tire tread, as shown.

FREDERICK RUFENACHT.
